(57) **CLAIM**(51) **LOC (10) Cl.** **23-04**

The ornamental design for a filter for removing particle matter, as shown and described.

(52) **U.S. Cl.**

DESCRIPTION

USPC **D23/365**

FIG. 1 is a perspective view of a filter for removing particle matter illustrating my new design;

(58) **Field of Classification Search**

FIG. 2 is a front view thereof;

USPC D23/355-365, 386-388, 314, 325,
D23/333-336; 55/478, 482, 483, 490, 497,
55/498, 520, 521, 529

FIG. 3 is a rear view thereof;

CPC B01D 46/00; B01D 46/0004; B01D 27/04;
B01D 27/06; B01D 39/00FIG. 4 is a top view thereof, the bottom view thereof being a
mirror image;

See application file for complete search history.

FIG. 5 is a right view thereof, the left view thereof being a
mirror image;(56) **References Cited**FIG. 6 is an enlarged view delimited by the four lines labelled
6 in FIG. 2;

U.S. PATENT DOCUMENTS

FIG. 7 is a cross-sectional view taken through line **7-7** of FIG.
